UNITED STATES PATENT OFFICE.

FREDERICK W. KOHAGEN, OF MARCY, MINNESOTA, ASSIGNOR TO NORTHERN SPIKE COMPANY, A CORPORATION OF MINNESOTA.

RAILROAD-SPIKE.

No. 904,489.

Specification of Letters Patent.

Patented Nov. 17, 1908.

Application filed September 16, 1907. Serial No. 393,132.

To all whom it may concern:

Be it known that I, FREDERICK W. KOHAGEN, a citizen of the United States, residing at Marcy, in the county of Lake and State of Minnesota, have invented certain new and useful Improvements in Railroad-Spikes, of which the following is a specification.

This invention relates to spikes, and more particularly to railroad spikes, and has for its object to provide a spike of this character with means whereby the spike will be prevented from working loose in the cross tie and loosing its hold on the rail.

15 Other objects and advantages will be apparent from the following description and it will be understood that changes in the specific structure shown and described may be made within the scope of the claim without departing from the spirit of the invention.

In the drawings forming a portion of this specification and in which like numerals of reference indicate similar parts in the several views, Figure 1 is a front elevation of the spike, Fig. 2 is a side elevation, Fig. 3 is a view showing the spike in use, Fig. 4 is a detail cross section on the line 4—4 of Fig. 2.

Referring now more particularly to the drawings, there is shown a spike 5, comprising a shank 6 and the head 7. The side walls 8 and 9 of the shank, are cut into as shown at 10, and barbs 11 are thus formed which lie with their outer edges in line with the sides 8 and 9 of the shank. The barbs 11 are preferably formed in an alternate arrangement, as shown, but it will be understood that the barbs may be arranged to produce the best results.

The head 7 of the spike extends transversely of the front and rear sides 12 and 13 of the shank, and a portion of the shank at the front and rear sides is broadened as shown at 14, to strengthen this end of the

shank. The rear portion of the head 7 is extended downwardly and rearwardly as shown, to form a prong 15, and this prong is preferably triangular in cross section, and consists of the sides 16, 17 and 18 which are tapered to a point as shown. A portion of the prong 15 at its upper inner edge is slotted as shown at 19, and this slotted portion of the prong extends inwardly of a portion of the head 7, as shown. The lower end of the shank 6 is beveled to a chisel edge, as indicated at 20, to facilitate driving the spike.

In use, the spike is driven into a tie A, as shown in Fig. 3 of the drawings, with the inner portions of the head 7 over the flange B of a rail C, and it will be seen that as the material of the tie enters the space between the sides 12 of the shank 6 and the inner edge of the prong 15, the prong will spread, and after the spike has been driven entirely into the tie a portion of this prong will lie parallel with the tie. It will be apparent that this prong serves as an efficient anchor for the spike against movement in one direction, and in a direction transversely of the prong, the barbs 11 serve as an additional anchor.

What is claimed is:

As an article of manufacture, a spike comprising a headed shank having a prong extending downwardly at an angle from the head, the head and the shank being kerfed at the juncture of the prong, said prong having a flat outer face and beveled side faces forming a knife edge adjacent the shank.

In testimony whereof I affix my signature, in presence of two witnesses.

FREDERICK W. KOHAGEN.
